REEL MOUNTING

Otto Wittel, Rochester, N. Y., assignor to Eastman Kodak Company, Rochester, N. Y., a corporation of New Jersey

Application December 8, 1938, Serial No. 244,649

4 Claims. (Cl. 242—70)

The present invention relates to a reel mounting for coaxially supporting a pair of film reels and more particularly to a reel engaging member of said mounting for forming a driving connection to one of the film reels and for spacing the film reels with respect to each other.

Reel mountings for coaxially supporting a pair of film reels are well known. It is also well known to provide in or on such reel mountings one or more reel engaging members which make a driving connection between the spindle and one of the film reels or which separate the film reels from each other. However, all of said known constructions are either rather complicated or else perform only one of the aforementioned functions.

The primary object of the present invention is the provision in a reel mounting of a reel engaging member which is pivotally connected at one end to the spindle member and which has at its other end a shoulder portion for engaging the axial opening in one film reel to form a driving connection and which has a tongue portion adjacent to said shoulder portion and for limiting the axial movement of either or both of said film reels.

Another object of the invention is the provision of a reel engaging member in a reel mounting and which is pivotally connected to the spindle member for rotation about an axis which is oblique to the rotational axis of the spindle member.

A further object of the invention is the provision in a reel mounting of a reel engaging member for driving one film reel and for spacing a pair of film reels from each other and which is movable into an overlying operative position with respect to the spindle member in such a manner that the axial opening of the driven film reel maintains the reel engaging member in such an overlying position.

Other and further objects of the invention will be suggested to those skilled in the art by the description which follows.

The above and other objects of the invention are fulfilled by a reel mounting assembly for coaxially supporting a pair of film reels and comprising a stationary support member, a spindle member journaled in said support member for rotation about an axis, and a reel engaging member pivotally connected at one end to said spindle member, having at its other end a shoulder portion and an adjacent tongue portion, which portions are operative respectively to engage one film reel for a driving connection thereto and

to limit the axial movement of both film reels when said reel engaging member overlies said spindle member, and which portions become inoperative and permit the removal of a film reel when the reel engaging member is swung through 180° into extended alignment with said spindle member. The removal of the film reel from the spindle member is greatly facilitated if the reel engaging member is mounted for rotation about an axis which is oblique to the rotational axis of the spindle member.

Reference is hereby made to the accompanying drawing wherein similar reference characters designate similar elements and wherein:

Fig. 1 is a top or end view of the reel mounting according to the invention with one flange of the driven reel broken away.

Fig. 2 is a longitudinal section through the reel mounting assembly of the invention.

Fig. 3 is a transverse section of the reel mounting assembly taken on the line 3—3 of Fig. 2.

It is to be understood that the reel mounting herein described and disclosed may be used on any type of photographic or motion picture apparatus which requires coaxial mounting of a pair of film reels so that one reel may rotate freely with respect to the mounting while the other reel is positively driven by the spindle member of the mounting.

In the illustrated embodiment of the invention a stationary support member comprises a wall 10 which is provided with a recess 12 and a bushing 11. The bushing 11 has a base 13 which is fastened to the wall 10 by screws 14 and has a sleeve portion 15 which is provided with an axial bore 16.

The spindle member is journaled in said support for rotation about an axis coaxial with the bushing 11. Such a spindle member 17 has a reduced bearing portion 18 fitting into the axial bore 16 of sleeve portion 15. A pulley 19 may be threaded onto the inner end of spindle member 17 and may be driven by a spring belt or other driving means for rotation of the spindle member. The spindle member 17 is also provided with an inclined surface 20, the purpose of which will be later explained.

The reel engaging member 21 is pivotally connected to the spindle member 17 by a pin 22 which extends into spindle member 17 at an oblique angle to the rotational axis thereof. The reel engaging member 21 has a shoulder portion 23 and an adjacent tongue portion 24. The reel engaging member 21 may be moved into an overlying or overlapping operative position with re-

spect to the spindle member 17 as shown in Fig. 1 and by the full lines in Fig. 2 or may be swung into an extended inoperative position in substantial alignment with the spindle member as indicated by the dotted lines in Fig. 2.

With the reel engaging member 21 in its extended or inoperative position, a film reel may be moved over said reel engaging member 21 and said spindle member 17 onto the sleeve 15 of bushing 11. The two film reels are preferably identical and each comprises a cylindrical hub member 25 and flanges 26 and 27 attached to opposite ends of said hub member 25. In a well known manner each flange 26 is provided with a round axial opening 28 and each flange 27 is provided with a square axial opening 29. Since one of the film reels is to function as a supply film reel and the other as a take up film reel, said film reels will be designated respectively as film reel S and film reel T. A friction drag is provided to prevent the supply film reel S from turning too freely upon the sleeve 15. Such a friction drag may be conveniently provided as a spring clip 30 snapped into an annular recess 31 in sleeve portion 15. Spring clip 30 has a corner portion 32 for cooperating with the square axial opening 29 in the film reel S.

The operation of the reel mounting assembly according to the invention will now be explained. The reel engaging member 21 is first swung into the extended inoperative position indicated by the dotted lines in Fig. 2. The film reel S may then be positioned on the sleeve portion 15 and the corner portion 32 of spring clip 30 insures that said reel S is inserted in the proper relation by entering the square axial opening 29 thereof. If the reel S is moved over the sleeve 15 in reverse position, the corner 32 of clip 30 will abut against the flange 26 and prevent complete insertion of the reel onto the sleeve 15. After the proper positioning of supply film reel S, the reel engaging member 21 may be moved into an overlying operative position with respect to the spindle member 17. This position is shown by the full lines in Fig. 2 from which it is apparent that the tongue portion 24 of reel engaging member 21 will now prevent removal of the reel S or axial displacement of reel S during its rotation. The film reel T is now placed upon the spindle member 17 and over the reel engaging member 21. Axial movement of the reel T is also limited by the tongue portion 24 which, therefore, acts to space the reels S and T with respect to each other. At the same time, the square axial opening 29 of the reel T fits over the shoulder portion 23 of reel engaging member 21 to form a driving connection from the spindle member 17 to the film reel T. Again, as an attempt is made to locate the reel T on the reel mounting in reverse position the shoulder portion 23 will engage against flange 26 and prevent complete and proper location of said film reel T.

The mounting of reel engaging member 21 for rotation about an oblique axis is not absolutely essential for the operation of the reel mounting assembly. However, such oblique mounting of reel engaging member 21 causes the same to be moved upon rotation into inoperative position opposite the end of the spindle member 17 so that the reel S can be more readily moved because of less interference between the shoulder portion 23 and tongue portion 24 and the axial openings in the flanges of said film reel S.

From the foregoing description, it will be apparent that one end of the reel engaging mem-

ber 21 performs two functions, one by virtue of shoulder portion 23 to form a driving connection between spindle member 17 and the square axial opening 29 of the film reel T, the other by reason of tongue portion 24 to limit the axial movement of film reels S and T and to space said reels with respect to each other. It should also be noted that the reel engaging member 21 is maintained in its overlying operative position by the axial opening 29 of the film reel T.

Other modifications of the invention will occur to those skilled in the art and the present invention is limited only by the scope of the appended claims.

Having now particularly described my invention what I desire to secure by Letters Patent of the United States and what I claim is:

1. A reel mounting for coaxially supporting a pair of film reels which are provided with axial openings, comprising a stationary support member, a spindle member having one end journaled in said support member for rotation about an axis, an arm having at one end a shoulder portion and an adjacent tongue portion, and a pivot for connecting the other end of said arm to the other unsupported end of said spindle member, said arm being movable into an extended inoperative position to permit removal of one of said film reels from said spindle member and being movable into an operative position with said shoulder and tongue portions adjacent said spindle member, said shoulder portion being arranged to fit into and be held in said operative position by the axial opening of the other film reel in which operative position said shoulder portion forms a driving connection between said spindle member and said other reel and said tongue portion limits the axial movement of either of said film reels.

2. A reel mounting for coaxially supporting a pair of film reels comprising a stationary support member, a spindle member having one end journaled in said support member for rotation about an axis, said support and spindle members being arranged to carry a pair of film reels in coaxial relationship, an arm having at one end a reel engaging portion, and a pivotal connection having an axis oblique to the rotational axis of said spindle member and for connecting the other end of said arm to the other unsupported end of said spindle member, said arm being movable into an extended inoperative position with said reel engaging portion substantially in axial alignment with said spindle member to permit easy removal of one of said film reels and being movable into an operative position with said reel engaging portion adjacent said spindle member, said reel engaging portion being arranged to fit into and be held in said operative position by the axial opening of the other film reel and to form a driving connection from said spindle member to said other reel.

3. A reel mounting for coaxially supporting a pair of film reels, comprising a stationary support member, a spindle member having one end journaled in said support member for rotation about an axis, said support and spindle members being arranged to carry a pair of film reels in coaxial relationship, an arm having at one end a shoulder portion and a tongue portion, and a pivotal connection between the other end of said arm and the other unsupported end of said spindle member and having an axis oblique to the rotational axis of said spindle member, said arm being movable into an overlapping position with said shoulder portion and said tongue portion at

one side of said spindle, said shoulder portion being formed to enter the axial opening in a film reel, and said tongue portion being formed to engage the side flanges and to limit the axial movement of either of said film reels.

4. A reel mounting for coaxially supporting a pair of film reels which are provided with axial openings, comprising a stationary support adapted to carry one of said film reels, a spindle member having one end journaled in said support for rotation about an axis, adapted to carry the other of said film reels and having on one side an inclined surface, an arm having at one end a shoulder and a tongue, and a pivot for connecting the other end of said arm to the other unsupported end of said spindle member and having an axis

oblique to the rotational axis of said spindle member and perpendicular to the inclined surface thereof, said arm being movable into an extended position with said tongue in substantial alignment with said spindle member to permit easy removal of one of said film reels and being movable into an operative position with said shoulder adjacent said inclined surface, said shoulder being arranged to fit into and be held in said operative position by the axial opening of the other film reel in which position said shoulder forms a driving connection to said reel and said tongue limits the axial movement of either of said film reels.

OTTO WITTEL. 15
